OVERSPEED CONTROL FOR HYDRAULIC TURBINES

Robert E. Brunswick Sharp, Philadelphia, Pa.,
assignor to Baldwin-Southwark Corporation,
a corporation of Delaware

Application September 28, 1935, Serial No. 42,590

3 Claims. (Cl. 253—117)

This invention relates generally to improved apparatus for reducing the runaway speed of hydraulic turbines, particularly low head adjustable runner blade turbines.

5 It is one object of my invention to provide improved means for controlling the runaway speed of a hydraulic turbine by automatically controlling the effective head on the runner independently of the position or adjustment of the gates or 10 runner blades in case an adjustable blade propeller type turbine is employed. A further and more specific object is to provide improved means having the foregoing mode of operation and adapted not to interfere with flow conditions 15 through the turbine during normal operation thereof.

Other objects and advantages will be more apparent to those skilled in the art from the following description of the accompanying drawings 20 in which:

Fig. 1 is a partial sectional view of a hydraulic turbine of the horizontal type employing my improved overspeed control;

Fig. 2 is an enlarged sectional view taken on the 25 line 2—2 of Fig. 1;

Fig. 3 is a sectional view of a vertical axis turbine employing my invention;

Fig. 4 is an enlarged sectional view of a solenoid controlled air valve employed in my improved 30 combination.

In the particular embodiments of the invention which are disclosed herein merely for the purpose of illustrating certain specific forms among possible others that the invention might 35 take in practice, I have shown in Fig. 1 a conventional type of horizontal hydraulic turbine having a turbine runner 1 which may be of the Francis, propeller or other type connected to a shaft 2 for driving a generator 3. As is usual in the form 40 of turbine setting shown, the headwater is indicated at 4 and tailwater at 5, these being connected by a suitable inlet 6 and draft tube or discharge passage 7. The details of construction of the apparatus above mentioned are well-known 45 and may be of various well-known types, and hence the same need not be described in further detail.

One element of my improved speed reducing apparatus comprises an air inlet pipe 8 having a lateral pipe 9 which terminates in the draft tube 7 preferably at a point spaced inwardly from the inner wall thereof. Pipe 9 as shown in Fig. 2 is preferably stream-lined in the direction of flow through the draft tube and is preferably slightly 55 angularly disposed to conform to the whirling

component of the water as it leaves the runner during normal operation. The entrance end of pipe 8, Fig. 4, is provided with a valve 10 which may be of the flap valve type pivoted at 11 and held in its normal horizontal closed position by 5 a latch 12. This latch may be controlled in any suitable manner but for purposes of illustration a solenoid 13 is provided. The solenoid is connected to a suitable power source through lines 14 and is controlled by any suitable speed responsive means diagrammatically shown for purposes of illustration as a centrifugal flyball governor 15 driven by the turbine through its shaft 2. The circuit for the solenoid may be connected to any suitable contacts 16 adapted to be closed 10 by a governor operated sleeve 17 moved axially by the governor flyballs whereby when a predetermined excess speed is reached, collar 17 will engage contact 16 and close the circuit for the solenoid, thereby releasing latch 12 and permitting 15 inlet valve 10 to fall open by gravity. Air is thereupon admitted through pipes 8 and 9 to the draft tube with the result that any vacuum therein is 20 broken. This results in a substantial reduction of the effective head from H_1 to H_2 , Fig. 1, and 25 thus reduces or limits the runaway speed of the runner.

Under excess speed conditions, the water leaves the runner with a large whirl component which causes the water to hug the wall of draft tube 7. 30 To overcome this condition, pipe 9 projects a sufficient distance inwardly of the draft tube wall to admit air to a more central portion of the draft tube, at least inside the zone of the more pronounced whirl in the water. Valve 10 may be 35 manually reset upon restoration of normal conditions. The invention is particularly applicable to siphon settings although it is equally applicable to other settings as shown in the vertical axis 40 turbine of Fig. 3, wherein the parts are given the same reference numbers as in Fig. 1.

From the foregoing disclosure, it is seen that I have provided a new and improved means for automatically reducing the runaway speed of a hydraulic turbine by positively reducing the effective head thereon but without the necessity of relying upon adjustment of the turbine gates or runner blades. Hence the component elements of the invention are simple in construction, operation and maintenance and are highly effective in 45 producing the desired control of the runaway conditions automatically upon occurrence thereof.

It will of course be understood that various changes in details of construction and arrangement of parts may be made by those skilled in the 50 55

art without departing from the spirit of the invention as set forth in the appended claims.

I claim:

5 1. In combination, a hydraulic turbine having a flow passage including a draft tube, a passage for admitting air into said draft tube to reduce the effective head on the turbine, a valve adapted either to completely open said air passage during overspeed or to completely close said passage during normal speed, and means for controlling said valve so that it is completely open automatically only upon occurrence of a predetermined speed

above normal and is thereafter independent of any further degree of speed.

2. The combination set forth in claim 1 further characterized in that said valve has provision for being reclosed only by manual operation after it is once opened.

3. The combination set forth in claim 1 further characterized in that said air passage extends inwardly of the draft tube beyond the wall thereof so as to be free of the excessive plural component of the water during overspeed operation.

ROBERT E. BRUNSWICK SHARP.
